METHOD FOR CONTROLLING WEFT ENDS IN WEFT REPLENISHING LOOMS

Application filed August 28, 1930. Serial No. 478,428.

This invention relates to improvements in the method of controlling weft ends extending from reserve bobbins held in a magazine, and it is the general object of the invention, 5 after tying the weft ends of two bobbins together, to act on the ends in such a way as to prevent the knot between them from being drawn into the cloth.

In my prior Patent No. 1,756,709 I have 10 shown the method of controlling weft ends which consists in tying the threads of two bobbins together so that when one is transferred the other will act as a thread holder therefor. The invention as set forth in that 15 patent has been successfully practiced in connection with fabrics which have a relatively coarse ground weave to support a pile surface and in such use there was no need for preventing the knot from entering the shed, the 20 principal concern being to have the knot as small as possible. In the production of finer fabrics, however, it is usual practice to have as few knots as possible in the weft threads and it is accordingly an important object of 25 my present invention to provide a method for acting on the tied weft ends which will cause a bend or similar deformation in said 30 ends so disposed as to hold the knot out of the cloth when the second of a pair of bobbins is transferred. It is of course important to prevent the knot from being drawn into the cloth when the first of a pair of bobbins is 35 transferred, but this can ordinarily be easily accomplished because the distance from the magazine to the adjacent selvage is generally longer than the distance from the knot to either bobbin measured along the weft ends. 40 With these and other objects in view which will appear as the description proceeds, my invention resides in the combination and arrangement of parts hereinafter described and set forth in the claims.

In the accompanying drawings, wherein a 45 convenient embodiment of my invention is set forth,

Fig. 1 is a diagrammatic vertical section through a magazine such as may be employed to practice my present method,

Fig. 2 is a front view of the structure shown 50 in Fig. 1,

Figs. 3, 4 and 5 are successive diagrammatic views showing the manner in which my method is employed, and

Fig. 6 is a detail of a device which prevents the knot from being drawn into the shed. 55

Referring to Figs. 1 and 2, I have shown a magazine M having a guideway 10 down which reserve bobbins may move by gravity toward a discharge opening 11. A yielding gate or door 12 may be used so that the lowest 60 bobbin may be moved by a transerrer 13 into a depleted shuttle 14. The bobbins are arranged in pairs and the weft ends of the bobbins of each pair are tied together. The upper and lower bobbins of each pair are 65 designated at B' and B², respectively.

Located near the bottom of the magazine is a weft end engaging device comprising an upright post 15 having secured thereto a bent wire 16 formed with an upwardly and forwardly inclined portion 17 terminating in a hook 18. The parts described may be related as shown in Fig. 3 and the invention may be practiced in connection with a set of warps W which are incorporated into a 70 cloth C at the fell F, the cloth having a 75 selvage S.

In carrying my invention into effect the reserve bobbins are placed in the guideway 10 in pairs with their tip ends preferably, 80 though not necessarily, pointed away from the selvage. The weft end E' of each bobbin B' is tied to the weft end E² of the corresponding bobbin B², so that the bobbins have their weft ends attached in pairs. The 85 point of junction between the weft ends is designated at 19 and may be a knot or any other type of union between the threads. The term "knot" as used herein is intended to designate any mode of attachment between 90 the weft ends, such as actual tying, twisting etc.

As the shuttle becomes depleted, well-known mechanism will be set in operation to force the lowest bobbin in the guideway into 95 the shuttle. As shown in Fig. 1 this will be a bobbin B² and the corresponding bobbin B' will remain in the magazine to act as a thread holder to cause unwinding of the weft from bobbin B² as the latter moves into the shed 100.

between the warps W, as shown in Fig. 3. The inclined wire guide 17 is so placed that as weaving continues the weft thread which extends from the remaining or lowest bobbin B² will move thereover as the cloth advances, until it assumes the position shown in Fig. 4. In this position the hook 18 will lie behind and over the thread, so that as the lowest bobbin B' is transferred at a later period in the operation of the loom and is moved into the warp from the dotted to the full line position shown in Fig. 5, said hook will engage the threads which are tied together and prevent the knot 19 from entering the shed.

15 Cloth of the type in the weaving of which my invention is particularly adaptable will ordinarily have very fine weft so that as the loom continues to run the loop of filling formed by the tied weft ends being attached to the selvage at two spaced points will break due to the resistance of the hook 18. If this mode of separating the weft ends from the hook be considered undesirable they may be 20 cut in any approved manner.

25 It is expedient, though not necessary, to have the weft ends E' and E² of a length substantially not greater than their bobbins and if desired these ends may be inserted within 30 the bobbins as set forth in my co-pending application Ser. No. 475,283. In any event, the length of the weft ends should be such that the knot 19 cannot be drawn into the warp when the first of a pair of bobbins is 35 transferred. In other words, the distance between the knot 19 and that point on the wound mass of weft on the remaining bobbin to which the weft E² is attached should be less than the distance from said point to the 40 selvage. In this way assurance is given that the knot will not be drawn into the shed by bobbin B².

45 While I have shown the knot as being between the wound bobbin B' and the selvage in Figs. 3 and 4, yet my invention can be practiced where for any reason, after the knot has been tied, one of the weft ends is wound back on its bobbin until the knot is wound on said bobbin where it will be less likely to 50 become undone if the mode of attachment is twisting.

55 The apparatus shown sets forth an approved manner of carrying my invention into effect, but is merely illustrative and the method disclosed herein may be carried out by the use of devices other than those set forth herein without departing from the scope of the invention. Although the drawings show a magazine having a single point of delivery, 60 yet the invention may be used on a double shuttle loom as contemplated in my aforesaid patent.

65 Having thus described my invention it will be seen that changes and modifications may be made therein by those skilled in the art

without departing from the spirit and scope of the invention and I do not wish to be limited to the details herein disclosed, but what I claim is:

1. The method of controlling weft ends in 70 weft replenishing looms, which consists in providing two reserve bobbins with their ends tied together in a knot, transferring one bobbin and leaving the other to act as a thread holder with the knot lying between the selvage and said other bobbin, and subsequently transferring the other bobbin and producing a bend in the weft at a point nearer the knot than the selvage to prevent the knot from being drawn into the shed by said other 80 bobbin.

2. The method of controlling weft ends in 85 weft replenishing looms, which consists in providing two reserve bobbins with their ends tied together in a knot, transferring one bobbin and leaving the other to act as a thread holder with the knot lying between the selvage and said other bobbin, and subsequently transferring the other bobbin and producing a bend in the weft at a point nearer 90 the knot than the selvage to prevent the thread between the selvage and the other bobbin from being drawn into the shed by said other bobbin.

3. The method of controlling weft ends 95 in weft replenishing looms, which consists in providing two reserve bobbins each with an extending weft end not substantially longer than the bobbin, uniting the weft ends in a knot, transferring one bobbin and leaving the 100 other to act as a thread holder therefor with the knot lying between the selvage and the other bobbin, subsequently transferring the other bobbin and producing a bend in the weft at a point nearer the knot than the selvage to prevent that part of the weft between the knot and selvage and also the knot from 105 being drawn into the shed by the other shuttle.

4. The method of controlling weft ends in 110 weft replenishing looms, which consists in providing two reserve bobbins each with a weft end of less length than the distance between the selvage and the point at which the end is attached to the wound mass of weft on 115 the bobbin, uniting the weft ends in a knot, transferring one bobbin and having the other to act as a thread holder therefor with the knot lying between the selvage and the other bobbin, subsequently transferring the other bobbin, and producing a bend in the weft at a point nearer the knot than the selvage to prevent the knot from being drawn into the shed with the other bobbin.

5. The method of controlling weft ends in 120 weft replenishing looms, which consists in providing two reserve bobbins each with a weft end extending from its tip end, temporarily supporting the bobbins with their tip ends pointed away from the selvage, 125

transferring one bobbin and leaving the other to act as a thread holder therefor with the knot located between the selvage and the other bobbin, subsequently transferring the 5 other bobbin, and producing a bend in the weft at a point nearer the knot than the selvage to prevent the knot from being drawn into the shed by the other bobbin.

6. The method of controlling weft ends in 10 weft replenishing looms, which consists in providing two reserve bobbins with their ends tied together in a knot, transferring one bobbin and leaving the other to act as a thread holder, and subsequently transferring 15 the other bobbin and producing a bend in the weft at a point nearer the knot than the selvage to prevent the knot from being drawn into the shed by said other bobbin.

In testimony whereof I have hereunto aff-
20 fixed my signature.

RICHARD GREENLEAF TURNER.
